UNITED STATES PATENT OFFICE

ALBERT P. LEONARD, OF JACKSON HEIGHTS, NEW YORK

SUGAR CANE MILL

Application filed October 12, 1925. Serial No. 61,896.

My invention relates to sugar cane mills and the like and particularly to crushing rolls for use therein and to the provision of means for collecting and withdrawing from the rolls the maximum quantity of cane juice. An important feature of my invention relates to the removal of the liquid from the upper strata of the crushed mat of bagasse or other material.

16 The ordinary sugar cane mill with which my invention is adapted to be employed consists of three crushing rolls mounted on parallel horizontal shafts supported in triangular relation. Of the two lower rolls the one 15 which first comes in contact with the cane is known as the feed roll, the other lower roll by which the pressed cane is ejected is known as the bagasse roll. Above and between the lower rolls is a top roll which presses down 20 upon the same with enormous force, crushing and mangling the cane into what is known as bagasse, squeezing out the cane juice, and rising and falling with variations in thickness of the matted bagasse. A turn plate is 25 located between the lower rolls to guide the cane from the feed roll to the bagasse roll and a pan is provided below the rolls to collect the expressed juice.

The pressure of the rolls upon the cane results in the squeezing out of a substantial 30 proportion of the juice and the crushing and matting of the fibrous structure of the cane. When compressed between the rolls and turn plate of the mill at the high pressure commonly used, the blanket of bagasse becomes 35 so densely packed as to have a structure approaching that of wood. The resistance of this densely matted fibrous material to the flow of juice therethrough is extremely high. 40 In grinding at high capacity and with consequently thick blankets of bagasse it is apparent that much of the juice in the upper strata of the bagasse will be prevented from flowing downward into the pan below and 45 that the operation of the mill will be rendered ineffectual to that extent.

In order to facilitate the collection of the juice which is in the lower portion of the mat, it has been customary in sugar cane mills 50 of this character to provide the lower rolls

with deep circumferential grooves which constitute open channels for the flow of juice into the pan. These grooves greatly increase the efficiency of the mill by effecting the removal of a greater proportion of the expressed juice than is possible in similar mills not provided with such grooves.

But no means has heretofore been known so far as I am aware for facilitating the removal of the juice which appears in the upper strata of the cane or bagasse adjacent the top roller. This juice being prevented by the density of the mat from passing downwardly to the lower rolls and so to the pan is in large part compelled to remain in the mat as it passes between the pressure rolls and is at once reabsorbed by the bagasse upon the removal of pressure as the material passes out of the mill. It has apparently been thought impossible to provide the top roll with passages for the removal of the juice as these passages would constitute open channels permitting flow of juice from the crushed cane at the inlet side of the machine to the bagasse at the outlet side of machine thereby in effect short circuiting the mill. For this reason existing devices are effectual to only a limited extent and it is necessary to pass the cane through a long series of mills in order to extract all of the juice which it is economically possible to obtain from the cane.

Objects of my invention include the provision of means for removal of the juice which finds its way to the upper portion of the bagasse mat in the sugar cane mill, for 85 making use of grooves in the top roll as well as in the lower rolls and for drawing off the juice collected in such grooves, and in general to provide means for making sugar cane mills of this type more efficient so that each 90 mill is capable of extracting a greater percentage of the expressed juice than heretofore and so that a lesser number of mills in series is capable of extracting the same or greater quantity of juice.

Other objects and advantages of the invention will appear from the following description taken in connection with the accompanying drawings.

Fig. 1 shows in vertical section a device 100

illustrating one embodiment of my invention. Fig. 2 is a vertical section of a portion of the upper roll of such device taken on line 2-2 of Fig. 1. Fig. 3 is a vertical elevation partly in section of an upper roll of such device embodying a modified form of my invention. Fig. 4 is end view of the roll shown in Fig. 3. Fig. 5 is a cross sectional view of the same on the line 5-5 of Fig. 3.

10 The cane mill shown in the drawings consists essentially of top roll 10 mounted on shaft 11, feed roll 12 mounted on shaft 13, bagasse roll 14 mounted on shaft 15, and turnplate 16 mounted on turn beam 17. The 15 sugar cane indicated at 20 is fed to the mill by chain 22 and is gripped between the top roll 10 and feed roll 12 at the zone indicated by numeral 24 where it is subjected to enormous pressure resulting in the crushing and 20 matting of the cane and the pressing out of a large portion of the juices therein.

The three rolls are normally geared together and driven in such manner that the top roll rotates clockwise as shown in the drawing while the lower rolls both rotate counter-clockwise. The surface of all three rolls may be serrated longitudinally or circumferentially in any desired manner to promote the crushing of the cane and expression of the juice. In addition all three rolls are provided with deep circumferential grooves indicated by the numeral 25. Scrapers 26 are preferably provided on fixed supports adjacent the lower rolls and adapted to slide through the grooves 25 during rotation of the lower rolls to keep the grooves relatively free of bagasse so that they may be open for the flow of juice. The bagasse crushed between the top roll and 30 feed roll in the zone 24 and between the top roll and bagasse roll in the zone 28 forms a dense mat which is carried through the mill by the rotation of the rolls. This mat packs against the shoulders 29 of the grooves 25 and bridges over the grooves but does not 35 ordinarily enter deeply into the grooves or block them up. Thus the grooves 25 provide channels for leading off into the pan 30 all juice pressed out of the cane which reaches the vicinity of the lower rolls.

As shown in Figs. 1 and 2, the grooves 25 in the upper roll 10 are each provided with a drainage element 32 fitting close to the bottom of the grooves around the lower portion 50 of the roll, all of said drainage elements communicating with a common header 34 which is in turn connected with a suction pump or other source of vacuum, not shown. The header 34 may be supported to move vertically with roll 10 in any appropriate manner. The drainage elements 32 are approximately U shaped as shown in Fig. 1 and are so formed as to fit slidably into grooves 25 in order that the top roll 10 may rotate freely 55 though the drainage elements themselves are

stationary in relation to the roll. The drainage elements are closed in cross section except in the zone indicated between the arrows A-A where they are closed only on three sides and are open at the side adjacent the bottom of the groove. A sufficient clearance is provided between the outer walls of the drainage elements 32 and the side walls of the grooves 25 to permit juice to flow between them but small enough to prevent the entrance of any but the finest particles of bagacillo or fine bagasse. The ends 37 of the drainage elements are preferably so shaped as to project outside of the surface of the roll 10 as at 33 to scrape any fine bagasse from the 75 walls or shoulders 29 of the grooves. Auxiliary cleaning devices 39 are provided to scrape and clean the remaining surface of the roll.

In the operation of my improved cane mill 85 the parts are set in motion and cane fed to the mill in the manner heretofore known. At the same time vacuum is applied to the header 34 and so to the interior of each drainage element 32. As the cane is crushed between the rolls the juice from the lower portion of the cane or bagasse works around the lower rolls over the surface and through the grooves 25 thereof into the pan 30. The juice contained in the upper portion of the cane and bagasse 90 works upwardly around the top roll and into the grooves 25 thereof. As the juice enters these upper grooves it is driven not only by the pressure of the juice behind it but also by the suction in the drainage elements to the bottom of the grooves and so through openings 35 to the interior of the drainage elements and thence to the header 34. A liquid collecting tank is inserted between the header 95 and the source of vacuum, or other means 100 provided for collecting the juice so drawn off.

Although I have described my invention in connection with a form of apparatus having mechanical means for removing the juice from only one of the three crushing rolls it will be apparent that either or both of the lower rolls may be provided with similar mechanical means for collecting the juice with the advantage that the juice so collected is substantially free of all bagasse or other solid 110 impurities.

The suction device may be a vacuum pump, a siphon or any other appropriate means for producing lower pressure in the outlet ends 115 of the tubes 32 than exists at the point of lowest pressure in the zone A-A.

It will be understood by those skilled in the art that there is a very substantial collection of juice in the upper portion of the cane at the zone indicated by numeral 36 in Fig. 1 and in the upper portion of the bagasse mat in the zone indicated by the numeral 38. Juices at 36 flow forward and downward through the uncompressed bagasse blanket and probably are essential to good macera-

tion. Therefore zone A—A is not shown extended to remove them. However, it may be found in practice desirable to extend the zone A—A to provide exit through tubes 32 of the juices in zone 36 as well as those in zone 38. The juices in these zones will readily enter the grooves in the top roll and will accordingly be separated from the bagasse and collected as described. In the absence of such grooves and collecting means in the top roll these juices would in large measure be carried through the mill and reabsorbed by the bagasse in the zone indicated by the numeral 40 and would have to be removed in a subsequent mill.

In the modified form of my invention shown in Figs. 3, 4 and 5 I employ an upper roll 42 provided with a plurality of longitudinal grooves 44 each groove being tapered from one end of the roll to the other so that at one end of the roll the grooves 44 are deep while at the other end they are relatively shallow. In each groove 44 I provide a bar 46 adapted to slide longitudinally and radially in the groove, the thickness of each bar being such as to fill the groove with only sufficient clearance to permit sliding of the bar in the groove. Each bar 46 is likewise tapered so that when lying in its corresponding groove with its tapered edge in contact with the tapered bottom of the groove the outer edge of the bar either lies in the cylindrical surface of the roll or parallel to that surface. The bars 46 extend at one end through flange 48 of the top roll into contact with a cam surface 50 which controls the movement of the bars relative to the top roll 42. The bars may operate with the cam surface in any desired manner. I have shown each bar 46 provided with a notch 52 adapted to fit over the cam surface 50 so that longitudinal movement of the bars in each direction is controlled by the cam. The bars which are adjacent the lower portion of the roll are moved by the cam surface 50 longitudinally toward the deep end of the grooves thereby permitting radial movement of the bars toward the center of the roll. The bars at the sides and top of the roll are moved longitudinally in the opposite direction by the cam surface 50 so that by force of the wedging action of the tapered surfaces of the bars and grooves their outer edges approach the outer cylindrical surface of the roll.

The cam surface 50 may be supported in any desired manner as by lugs 54 attached to the frame upon which the top roll is supported.

The operation of this form of the invention is as follows:

As the top roll rotates and each bar 46 approaches the crushing zone it is drawn longitudinally with respect to its grooves and by reason of its tapered form is permitted to move at the same time radially inward there-

by producing an open channel running longitudinally of the roll, the outer edge of the bar forming the bottom of the channel. The crushing pressure forces juice and bagasse from the top of the mat into the channel so formed, the bagasse bridging over the channel and the juice flowing into it under enormous pressure. The juice is thus permitted to flow longitudinally of the roll through the passage and escape through spaces 55 and 56 in the flanges 48 and 58 respectively of the top roll. Any appropriate means may be provided for collecting and withdrawing the juice which is thus forced out at the end of the top roll. As the top roll rotates further and the bar emerges from the crushing zone it is moved longitudinally by the cam surface 50 and by wedging action it is moved at the same time radially outward thereby scraping the sides of the groove and forcing out any bagasse which has adhered to the groove. Thus when the bar in question rotates once more into the crushing zone and moves endwise and radially to form an outlet passage for the juice as described the outlet passage is clean and free of bagasse and effective for the purpose desired. Without some such means for scraping and cleaning the groove to remove accumulated bagasse the passage would become clogged with bagasse and would shortly become useless.

In apparatus embodying my invention it will be seen that the proportion of the total moisture removed in each mill is very substantially greater than in mills heretofore known and that important economies in operation and capital expenditure are thereby made possible.

It will of course be understood that the foregoing description of my invention and the illustration of a device embodying it in the drawings are not intended as limitations of the invention and that a wide variety of changes and modifications may be made in the structure and operation thereof without departing from my invention as defined in the appended claims.

What I claim and desire to secure by Letters Patent of the United States is:—

1. In a mill for extracting liquid from fibrous material, a pair of crushing rollers, one of said rollers having passages for receiving liquid expressed from the crushed fibrous material, and means lying substantially within said passages for permitting flow of liquid into said passages and preventing passage of any but the finest particles of fibrous material.

2. In a mill for extracting liquid from fibrous material, a pair of crushing rollers, one of said rollers having passages for receiving liquid expressed from the crushed fibrous material, and conduits arranged in said passages for withdrawing liquid therefrom, said conduits being spaced from the

walls of the passages sufficiently to permit flow of liquid and to prevent passage of any but the finest particles of fibrous material.

3. In a mill for extracting liquid from fibrous material the combination with upper and lower crushing rolls of grooves in the upper crushing roll providing channels for the exit of liquid from the upper strata of the crushed fibrous material and means for removing fibrous material adhering to the sides of said grooves.

4. A mill for extracting liquid from fibrous material including upper and lower crushing rolls, grooves in the upper crushing roll providing channels for the exit of liquid from the upper strata of the crushed fibrous material, means for removing the liquid which enters such grooves and means for removing fibrous material adhering to the sides of said grooves.

5. A mill for extracting liquid from fibrous material including upper and lower crushing rolls, grooves in the surface of the upper crushing roll providing channels for the exit of liquid from the upper strata of the crushed fibrous material, pressure actuated means for removing the liquid from such grooves and means for removing fibrous material adhering to the sides of said grooves.

30 6. A mill for extracting liquid from fibrous material including a crushing roll, grooves in such roll providing drainage for such liquid, pressure actuated means for removing the liquid from such grooves and means for removing fibrous material adhering to the sides of said grooves.

40 7. The combination with a crushing roller and grooves therein of means for withdrawing liquid from said grooves having tubes communicating therewith and with a suction device and means for removing fibrous material adhering to the sides of said grooves.

45 8. The combination with a crushing roller and grooves therein of means for withdrawing liquid from said grooves including tubes communicating therewith, means for maintaining lower pressure at another portion of said tubes than at the point of their communication with said grooves and means for removing fibrous material adhering to the sides of said grooves.

50 9. The combination with a crushing roller and circumferential grooves in the surface thereof, of means for withdrawing liquid from said grooves including tubes lying partially within said grooves and communicating therewith adjacent the bottom of said grooves, said tubes being slightly smaller than said grooves to provide clearance for the flow of liquid but to prevent the entrance of any but the finest particles of solid matter.

60 10. The combination with a crushing roller and circumferential grooves in the surface thereof, of means for withdrawing liquid from said grooves including tubes adapted to

lie within said grooves adjacent the crushing zone, said tubes communicating with said grooves in the said zone and means for maintaining lower pressure at another portion of said tubes than at the point of their communication with said grooves to produce flow of liquid therethrough.

70 11. The combination with a crushing roller and circumferential grooves in the surface thereof, of means for withdrawing liquid from said grooves including stationary tubes adapted to be within said grooves adjacent the crushing zone, said tubes communicating with said grooves adjacent the bottoms thereof in the said zone and communicating elsewhere with a suction device.

75 12. A liquid removing element for a roll mill including a series of parallel tubes, means for securing the same to the mill, said tubes being arc-shaped in part to lie adjacent to the surface of a roller of the said mill and being open through a portion of said arc.

80 13. In a mill for extracting liquid from fibrous material, the combination with a crushing roll of means lying substantially within the periphery of said roll and providing an exit for liquid crushed from such material, said means also constituting a scraper to separate said material from said roll.

85 14. In a mill for extracting liquid from fibrous material, crushing means comprising a pair of relatively movable rollers, and means for withdrawing liquid expressed from the crushed material, said means moving with one of said rollers and removing material adhering thereto.

90 15. In a mill for extracting liquid from fibrous material, a pair of superposed crushing rollers, the upper of said rollers having superficial grooves for receiving liquid expressed from the upper strata of the crushed fibrous material, means for withdrawing from said grooves liquid accumulated therein and means for removing fibrous material adhering to the sides of said grooves.

95 16. In a mill for extracting liquid from fibrous material, a pair of crushing rollers, one of said rollers having superficial grooves, and inwardly facing arcuate troughs in said grooves for withdrawing therefrom liquid accumulated therein, the edges of said troughs being spaced from the walls of said grooves a sufficient distance to permit flow of liquid therebetween and prevent passage of any but the finest particles of fibrous material.

100 In testimony whereof, I have signed my name to this specification.

ALBERT P. LEONARD.
